UNITED STATES PATENT OFFICE.

JAMES W. CLARKSON AND CHRISTOPHER A. DIMLER, OF WASHINGTON, DISTRICT OF COLUMBIA.

APPARATUS FOR PROTECTING BANKS AND THE LIKE.

1,419,491.

Specification of Letters Patent. Patented June 13, 1922.

Application filed March 23, 1921. Serial No. 454,894.

To all whom it may concern:

Be it known that we, JAMES W. CLARKSON and CHRISTOPHER A. DIMLER, citizens of the United States, residing at Washington, in the District of Columbia, have invented certain new and useful Improvements in Apparatus for Protecting Banks and the like, of which the following is a specification.

10 This invention relates to new and novel means especially designed to be installed in banks, loan and trust companies, post offices, and other places handling large cash receipts, as a protection for the employees thereof against robberies or hold-ups.

15 The prime object of our invention is to provide novel, simple, economical, durable and efficient means wherein an agent will be suddenly discharged into the face of a bandit or robber to render him unconscious or blind, and simultaneously there will be operated a shield to protect an employee from a flying bullet or bullets which may be fired by said bandit or robber.

20 This invention provides an apparatus wherein receptacles containing an agent, preferably in powdered form, such as Cayenne pepper, are suitably arranged at convenient points at the various windows of a bank or similar institution, each of said receptacles being provided with a blower, so that if persons should attempt to rob or hold up any one or more of the employees at the various windows, the contents of any 25 one or a series of the receptacles may be blown therefrom and directed into the robbers' faces to render them helpless or blind, a protecting shield in front of the employee being simultaneously operated.

30 Another object of this invention is to provide a bank protecting device which can be readily installed in any bank, cashiers' apartments, or other similar places, and which when operated will perform the 35 double function of rendering robbers helpless and at the same time protecting the employee from bodily harm.

35 The foregoing and such other objects as may appear from the ensuing description 40 are accomplished by the novel features of construction, arrangement, location and combination of parts hereinafter more fully described, illustrated in the accompanying drawings, and particularly pointed out in

the claims appended hereto, it being understood that slight changes in the precise form, proportions, and minor details of construction may be resorted to without departing from the spirit or sacrificing any of the advantages of the invention. 55

In the accompanying drawings forming a part of this specification, it will be seen that:

Figure 1 is an elevation showing a portion of a bank fixture equipped with the apparatus embodying our invention. 60

Figure 2 is an enlarged sectional elevation taken through the receptacle and a portion of the bank fixture showing the means for discharging the powdered material within said receptacle. 65

Figure 3 is an enlarged transverse section taken through the receptacle and casing therefor, showing the casing partly broken away. 70

Figure 4 is an end elevation of the receptacle removed from its casing with the funnel portion broken away. 75

Figure 5 is an enlarged elevation showing a portion of the protecting shield in an elevated position with its operating chains secured thereto and the bank fixture and a portion of said shield broken away. 80

Figure 6 is a horizontal section taken on the plane of the dotted lines 6—6, Figure 5.

Figure 7 is a sectional elevation taken on the plane of the dotted lines 7—7, Figure 5. 85

Figure 8 is an enlarged sectional elevation of the lower portion of the bank fixture and protecting shield showing the treadle operating means secured thereto with the upper portion of said shield and the fixture broken away. 90

Figure 9 is a transverse section through the lower portion of the fixture showing the treadle means for releasing the protecting shield, and 95

Figure 10 is a similar view showing the protecting shield in its released position.

Similar numerals of reference are employed to designate like parts throughout the several views of the drawings. 100

In the embodiment of our invention as illustrated, and which shows a preferred construction, the numeral 1 indicates the fixture of a bank or the like, which fixture includes a plurality of receptacles 2, adapted to contain a powdered material, such as Cayenne pepper, one of which being suitably 105

mounted at the most desirable point within said fixture at each side of a window or other opening formed therethrough, each receptacle being provided with a front plate 5 3 provided with a series of staggered openings 4 so that the powder contained within the receptacle may be discharged through the various openings and into the face of the would-be robbers.

10 Each receptacle 2 is supported within the fixture 1, by a casing 5 fixedly secured to the fixture, said casing being provided with a plurality of bearing members 6 adapted to support an upper shaft 7 and a lower shaft 15 8, said upper shaft 7 passing centrally through the receptacle with its outer end mounted in the bearing 8 formed on the inner face of the front plate 3, the latter being secured to the front end portion of the receptacle, which is passed through an opening formed in the casing and seated within an opening formed through the front of the fixture. Fixedly mounted on each upper shaft 7 is a rotatable fan or blower 9, which 20 25 when caused to revolve, by the means hereinafter described, is adapted to operate a slideable valve 10 normally closing the inlet formed between the funnel 11 and the outer casing of the receptacle, thereby forcibly 30 35 and rapidly discharging the powder within the receptacle and simultaneously admitting additional powder within the receptacle to be discharged.

Fixedly secured to the inner end portion 35 of the shaft 7 is a small gear-wheel 12 adapted to engage and mesh with a large gear wheel 13 fixedly mounted on the lower shaft 8, and rigidly secured to the shaft 8, intermediate its ends is a sprocket wheel 14 40 45 which engages with a sprocket chain 15, said chain engaging with another idler sprocket wheel 16 carried by a shaft mounted on the casing 5 and adapted to convey the said chain out of the path of the receptacle.

It will be perceived that one end of each of the sprocket chains 15 is secured to the upper end of a hardened steel plate 17 adapted to entirely close the opening or window formed through the fixture when it reaches its elevated position, thereby creating a protective shield for the employee behind the window or opening, while the other end of each of the chains 15 is secured to a 50 55 heavy weight 18.

Secured at the bottom portion and within the inner side of the fixture 1, extending any suitable distance within the apartment, is a movable or rocking treadle bar or rod 19 60 fixedly secured to one end of a plurality of connecting links 20, the latter being rigidly secured to a stationary rod 21 extending lengthwise through the fixture, and connected to the treadle bar or rod 19, at the 65 central portion of each window or opening,

is one end of a link 22, the other end being connected to a latch 23 adapted to engage with a keeper 24 centrally and fixedly secured to the lower end of the steel shield plate 17, and adapted to hold said plate 70 normally in its lowermost position with its lower end resting on the angle bars 25 fixedly secured to the fixture. The latch 23 is pivotally secured at its lower end to the fixture at 26, while its upper end overlaps the 75 keeper carried at the lower end of the plate 17, and secured intermediate the ends of said latch is a coiled spring 27, the other end of said spring being fixedly secured to the fixture at 28.

It will be seen that one end of each chain being secured to the upper end of the shield plate and passing upward through the heading 29 of the fixture and over the sprocket pulley 30 supported upon the upper face 85 of said heading, thence downward through the heading into engagement with the idler sprocket wheel 16 and the sprocket wheel 14, with its other end secured to a heavy weight 18, said weights being considerably 90 in excess of the weight of the protecting shield plate 17, that when a robber approaches the window and demands that the employee throw up his hands, it will simply be necessary for said employee to throw 95 up his hands and at the same time depress the treadle with one foot, thereby releasing the latch which locks the weights in their uppermost position, thus allowing the 100 weights to suddenly fall thereby causing the 105 downward movement of the chair to impart a rapid rotary motion to the fan or blower within the receptacle and discharge the powdered pepper into the face of the robbers, and simultaneously elevate the protecting 110 steel shield within the guideways formed in the window frame to protect the employee from flying bullets which may be discharged by the robbers or their assistants, which will be readily understood.

As shown in Figs. 9 and 10, the treadle rod is adapted to have a swinging or rocking movement within the supports 33 which are provided with a slot 34 adapted to limit the upward and downward movement of said 115 treadle rod.

To the inner face of the heading 29 of each window is preferably secured a cushion 31 formed of any suitable material to relieve the concussion produced by the contact of the upward thrust of the contact of the upper edge of the protecting shield when suddenly shifted to its uppermost position, and within the base portion of the fixture is suitably secured in vertical alinement with each of the weights 18 a buffer 32 adapted to absorb the jar caused by the sudden dropping of the weights into contact therewith.

It will be understood that a single treadle rod or bar may be extended along a series 130

of windows or openings, whereby the depression of said treadle will simultaneously actuate a series of powder receptacles and protecting steel shields for the purpose herein described.

Having thus described our invention, what we claim and desire to secure by Letters Patent is:—

1. An apparatus of the character described comprising a fixture having a window opening therein, a powder receptacle arranged adjacent said window opening and provided with a discharge outlet, means mounted within the receptacle for discharging its contents, a metallic shield adapted to close said window opening, and means adapted to simultaneously actuate the metallic shield and the receptacle discharging means.
2. An apparatus of the character described, comprising a fixture having a window opening therein, a powder receptacle arranged adjacent said window opening containing a powder and provided with a series of outlets, rotary discharging means mounted within the receptacle, a metallic shield adapted to close said window opening, and means for simultaneously actuating the metallic shield and said discharging means.
3. An apparatus of the character described, comprising a fixture having a window opening therein, a powder receptacle fixedly secured adjacent said window opening and having a series of outlets, revolving means mounted within each receptacle for discharging its contents, a reciprocating metallic shield adapted to close said window opening, and means for simultaneously operating the said shield and discharging means.
4. An apparatus of the character described, comprising a fixture having a window opening therein, a powder receptacle fixedly secured adjacent said window opening within the fixture and having a series of outlets, rotating means adapted to operate a slide valve and to discharge the contents of the receptacle, a reciprocating hardened steel shield adapted to close said window opening when elevated, and means for elevating said shield and simultaneously actuating the rotating means.
5. An apparatus of the character described, comprising a fixture having a window opening therein, a powder receptacle fixedly secured adjacent said window opening and provided with a series of outlets, means mounted on a shaft within the receptacle for discharging the contents of said receptacle, a metallic shield mounted within the fixture and adapted to close said window opening, and means mounted within the fixture for simultaneously actuating the said shield and discharging means.
6. An apparatus of the character described, comprising a fixture having a window opening therein, a powder receptacle arranged adjacent said window opening and provided with a series of outlets, means mounted on a shaft within the receptacle for discharging the contents of said receptacle, a metallic shield mounted within the fixture and adapted to close said window opening, and means mounted within the fixture for simultaneously actuating the said shield and discharging means.
7. An apparatus of the character described, comprising a fixture having a window opening therein, a powder receptacle arranged adjacent said window opening and provided with a series of outlets, means mounted on a shaft within the receptacle for discharging the contents of said receptacle, a metallic shield mounted within the fixture and adapted to close said window opening, and means mounted within the fixture for simultaneously actuating the said shield and discharging means.
8. An apparatus of the character described, comprising a fixture having a window opening therein, a powder receptacle arranged adjacent said window opening and provided with an outlet, means mounted within each receptacle for discharging its contents, a shield for closing the window opening, means for locking said shield in its lowermost position, means for releasing said shield, and means for simultaneously actuating said shield into an elevated position and operating the discharging means.
9. An apparatus of the character described, comprising a fixture having a window opening therein, a powder receptacle arranged adjacent said window opening and provided with an outlet, means mounted within said receptacle for discharging its contents, a shield for closing the window opening, means for locking the shield in its lowermost position, a treadle with means connected thereto for releasing said locking means, and means for simultaneously actuating said shield into its elevated position and operating the discharging means.
10. An apparatus of the character described, comprising a fixture having a window opening therein, a powder receptacle arranged adjacent said window opening and provided with outlets, means for discharging the contents mounted within said receptacle, a metallic shield for closing the window opening, means for locking the shield in its lowermost position, a swinging treadle for releasing said locking means, and means for simultaneously moving said shield to its uppermost position and actuating the discharging means.
11. An apparatus of the character described, comprising a fixture, having a plurality of window openings therein, a powder receptacle arranged adjacent each of said window openings and having a series of outlets, means within the receptacle for discharging the contents of said receptacle, a metallic shield mounted within the fixture and adapted to close each of said window openings, and means mounted within the fixture for simultaneously actuating the said shield and discharging means.

dow opening therein, a powder receptacle fixedly secured adjacent said window opening, and having a series of outlets, means mounted within each receptacle for actuating a slide valve and for discharging the contents of the receptacle, a metallic shield mounted within the fixture, means for holding said shield in its lowermost position, and means for simultaneously elevating said shield to its uppermost position and actuating the discharging means.

7. An apparatus of the character described, comprising a fixture having a window opening therein, a powder receptacle secured adjacent said window opening and having a discharge outlet, a metallic shield adapted to close said window opening, means within each receptacle for discharging its contents, and means for simultaneously actuating the said shield and discharging means.

8. An apparatus of the character described, comprising a fixture having a window opening therein, a powder receptacle secured adjacent said window opening and provided with an outlet, means mounted within each receptacle for discharging its contents, a shield for closing the window opening, means for locking said shield in its lowermost position, means for releasing said shield, and means for simultaneously actuating said shield into an elevated position and operating the discharging means.

9. An apparatus of the character described, comprising a fixture having a window opening therein, a powder receptacle arranged adjacent said window opening and provided with an outlet, means mounted within said receptacle for discharging its contents, a shield for closing the window opening, means for locking the shield in its lowermost position, a treadle with means connected thereto for releasing said locking means, and means for simultaneously actuating said shield into its elevated position and operating the discharging means.

10. An apparatus of the character described, comprising a fixture having a window opening therein, a powder receptacle arranged adjacent said window opening and provided with outlets, means for discharging the contents mounted within said receptacle, a metallic shield for closing the window opening, means for locking the shield in its lowermost position, a swinging treadle for releasing said locking means, and means for simultaneously moving said shield to its uppermost position and actuating the discharging means.

11. An apparatus of the character described, comprising a fixture, having a plurality of window openings therein, a powder receptacle arranged adjacent each of said window openings and having a series of outlets, means within the receptacle for discharging the contents of said receptacle, a metallic shield mounted within the fixture and adapted to close each of said window openings, and means mounted within the fixture for simultaneously actuating the said shield and discharging means.

charging its contents, a metallic shield for closing each window, means for locking the shield in its lowermost position, means connected at one end of the said shield and at its 5 other end to a heavy weight for simultaneously actuating said shield, and discharging means, means for releasing said locking

means, means within the fixture forming a cushion contact for the shield, and means at the bottom of the fixture forming a shock 10 absorber for the weights.

JAMES W. CLARKSON.
CHRISTOPHER A. DIMLER.
